(57) **CLAIM**

The ornamental design for a magnetic pistol mount, as shown and described.

DESCRIPTION

FIG. 1 is a front, right side, top perspective view of a first embodiment of a magnetic pistol mount showing my new design;

FIG. 2 is a rear, left side, bottom perspective view thereof; FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded front, right side, top perspective view thereof;

FIG. 10 is an exploded rear, left side, bottom perspective view thereof;

FIG. 11 is a front, right side, top perspective view of a second embodiment of a magnetic pistol mount showing my new design;

FIG. 12 is a rear, left side, bottom perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is an exploded front, right side, top perspective view thereof; and,

FIG. 20 is an exploded rear, left side, bottom perspective view thereof.

The broken lines depict portions of the magnetic pistol mount that form no part of the claimed design.
